M. ROSENWASSER

PNEUMATIC INSOLE FOR SHOES

Filed March 3, 1922

INVENTOR:
MORRIS ROSENWASSER

BY

Charles H. Weller
ATTORNEY.

UNITED STATES PATENT OFFICE.

MORRIS ROSENWASSER, OF NEW YORK, N. Y.

PNEUMATIC INSOLE FOR SHOES.

Application filed March 3, 1922. Serial No. 540,711.

To all whom it may concern:

Be it known that I, MORRIS ROSENWASSER, a citizen of the United States, residing at New York, in the county and State of New York, have invented certain new and useful Improvements in Pneumatic Insoles for Shoes, of which the following is a specification.

This invention relates to pneumatic treads or insoles for shoes, slippers, and other articles of foot-wear.

One of the objects of the invention is to provide a new and improved pneumatic insole or tread which can be manufactured and sold as a separate article, or made a part of a shoe, slipper, or other article of footwear.

Another object of the invention is to provide as an article of manufacture, a shoe wherein the new and improved insole is incorporated so that the covering for the foot can be worn with a greater degree of comfort than is possible with the pneumatic insoles as heretofore constructed.

Another object of the invention is to provide a pneumatic tread or insole of such form that the major part of the cushioning effect is located under the arch or instep of the foot.

Another object of the invention is to provide a new and improved insole of the pneumatic type, so constructed that the weight of the foot will anchor it firmly in place, so that a cushioning effect is provided without any tendency of the foot to move backwardly 35 and forwardly in the shoe.

Another object of the invention is to provide a new and improved insole of the cushion type, in which a pneumatic tread is provided of such character that the major cushioning effect occurs under the arch or instep, so that the toes of the foot are not forced upwardly against the inner side of the shoe with accompanying rub and chafing.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claim.

In the accompanying drawing, wherein I have illustrated preferred forms of embodiment of my invention:

Figure 1 is a perspective view of my im-

proved pneumatic insole, with the covering removed, and shown dissociated from the article of footwear in which it is intended to be incorporated.

Figure 2 is a longitudinal section of the completed tread, on the line 2—2 of Figure 3.

Figure 3 is a cross-sectional view of the insole taken on the line 3—3 of Figure 2; and

Figure 4 is a longitudinal cross-sectional view of a shoe provided with the improved insole, the foot being inserted in the shoe so as to show the distribution of the air-cushion under the weight of the foot.

Referring now to the drawing, wherein similar reference characters refer to similar parts throughout the several views thereof, the numeral 1 denotes one of the walls of the cushion, composed of a resilient impervious material, such as sheet rubber, and corresponding in outline to the contour of the human foot. Corresponding to the wall 1 there is a similar wall 2, provided, however, along its margin with an outwardly extending flange 3, the flange 3 extending from a point substantially where the ball of the foot rests upon the insole backwardly around the heel, and forwardly to the point of contact of the ball of the foot.

In constructing the insole the two opposed walls are placed one upon the other, and the lateral flange bent over the upper wall, and inwardly as shown in Figure 1, in which position the two walls are vulcanized together along their margins, in such a way, however, as to confine a quantity of air within them. From the point of contact of the ball of the foot forwardly to the toe of the insole, the two walls are forced into contact and vulcanized or otherwise joined together, so as to form a flat homogeneous extension, the two walls being in contact so that no air is contained between them in the extension. At the heel there is provided a reinforcing strip 4, which overlies the union of the flange 3 with the wall 1, as shown. It will be understood that the heel takes up a great deal of the wear due to the alternate pressure and release of the heel of the foot in walking, and the strip 4 provides added protection at the point where this wear occurs.

The air confining sack, as shown in Figure 2, is provided with an outward covering 5, made of a flexible inelastic absorbent material, such as is provided by certain

kinds of leather. The covering 5 is made of two halves, one being provided with marginal extensions 6, as shown in Figure 2, which are folded over the inner sack, the 5 corresponding half of the covering 5 then being laid thereon and united along its margin, as indicated at 7 in Figure 3. It will be seen that by this construction I have provided a resilient air cushion covered by 10 a protective covering of similar characteristics to those ordinarily used as insoles.

The new and improved tread or insole is shown in use in Figure 4, it being laid loosely in the interior of the shoe, the flat extension 15 projecting into the toe of the shoe. It will be noted that in such position the flat extension, which as stated, is formed by the homogeneous union of the opposed walls of the sack, begins at a point 8, where the 20 ball of the foot presses downwardly when weight is put on it. The extension projects forwardly from this point into the toe of the shoe, so that the only cushioning effect from the point 8 forwardly is produced 25 by the natural resiliency of the walls of the sack. It will be seen also that the weight of the heel, as indicated at 9, tends to force the air forwardly until the main body of air is contained within the sack at a point 30 10, which is directly under the arch or instep.

When the shoe is used in walking, the weight comes first at the point 9, forcing the air forwardly as the foot is rocked. 35 The ball of the foot engages the pneumatic insole at 8, and the ball of the foot and the toes serve to provide a firm anchor so that the insole or tread cannot be moved relatively to the shoe. Inasmuch as the insole 40 contains no air from a point corresponding to the ball of the foot forwardly, there is no tendency for the toes to be forced up against the inner side of the toe cap with resultant chafing.

45 It will be seen also that with my new and improved insole there is no tendency for the foot to be shoved farther into the shoe during walking, the result which would follow naturally were the air cushion provided throughout the entire length of the insole. The flat extension provides a positive anchor both for the insole and the foot, and as will be seen the main cushioning effect is produced under the arch, so that I secure an air cushion arch support, as well as 50 a cushioned tread.

55 Inasmuch as the pneumatic envelope or sack is made of a resilient material, it readily adapts itself to the surface of the foot and provides a perfect cushion with an in-

creased cushioning effect at the point where such support is most needed.

While I have shown my improved pneumatic cushion composed of two separate walls united along their margins, I do not 65 intend to be limited to this construction, inasmuch as I contemplate also making the entire envelope of an integral construction.

I also contemplate the union of the two walls forming the sack as herein shown by 70 other than vulcanizing. Nor do I intend to be limited to the use of any definite quantity of air or other compressible fluid located within the envelope. The quantity of air therein contained may be varied in accordance with the demands of the service to which the pneumatic tread is to be put. 75 Any construction by which a quantity of compressible fluid may be contained within an envelope or sack, which is in turn provided with an anchoring extension as shown, will produce the results which I have in mind.

As many changes could be made in this construction without departing from the 80 scope of the following claim, it is intended that all matter contained in the above description or shown in the accompanying drawing shall be interpreted as illustrative only and not in a limiting sense. 85

Having thus described my invention what I claim as new and desire to secure by Letters Patent is:—

A pneumatic insole, comprising a flexible air sack conforming to the contour of the 90 interior of a shoe, the said sack consisting of upper and lower members substantially as long as the interior of the shoe, the said members being closed one upon the other and secured together permanently from the 100 toe end of the insole to the instep, the remaining portion of the said sack containing a movable air charge, the said air charge being normally of equal depth from the 105 said closed toe portion of the insole to the heel portion thereof when the foot of the wearer of the shoe is at rest thereon, and the said air charge being pressed forward by the heel of the foot when walking and forced into an air body of greater than the normal depth and localized directly below the instep and operating to exert a pressure upwardly upon the sole of the foot at each step.

In testimony whereof, I affix my signature 115 in the presence of two witnesses.

MORRIS ROSENWASSER.
